UNITED STATES PATENT OFFICE.

LEO DAFT, OF GREENVILLE, NEW JERSEY.

ELECTRIC-ARC LAMP.

SPECIFICATION forming part of Letters Patent No. 276,567, dated May 1, 1883.

Application filed February 13, 1882. (No model.)

To all whom it may concern:

Be it known that I, LEO DAFT, a subject of the Queen of Great Britain, residing at Greenville, in the county of Hudson and State of New Jersey, have invented new and useful Improvements in Electric Lamps, of which the following is a specification.

This invention consists in combining with the axial magnet of an electric lamp an interior movable coil attached to the core of the axial magnet. This interior coil is placed in a shunt-circuit around the circuit passing through the coil of the axial magnet.

The invention also consists in a new and simple arrangement of magnetic clutch, the said clutch being attached to the core of the axial magnet, and being influenced by the varying magnetism of said core.

This invention is illustrated in the accompanying drawing, which represents a vertical section.

In this drawing, the letter A designates an axial magnet, B its soft-iron core, and C the carbon-holder, which extends loosely through the core, and is connected to the same by the rings *a a*, which embrace the carbon-holder, and each of which is connected to a lever, D. These levers are connected to an insulating frame or support, B', on the core B by pivots *b*, and their upper ends are made concave to correspond to the circumference of the core, and they form armatures which are attracted by the core whenever the same becomes magnetized. To the core B is firmly secured a plate, P, which rests upon springs Q for the purpose of balancing the weight of the core. The carbon-holder is guided by grooved rollers *r r*. As long as the electric arc remains in its normal condition the attractive force of the core B on the armature D retains the carbon-holder firmly in position; but whenever the attractive force of the core decreases, the armatures D release the carbon-holder, so that the same slides down. As soon as the proper electric arc is restored the downward movement of the carbon-holder is again arrested, and in this manner the electric arc is controlled automatically. In the core B is a recess, *c*, and in this recess is situated the regulating-helix E. This helix is situated in a shunt-circuit around the main helix A, and it is made of very fine

wire, so that the resistance is much greater than that of the main helix, the proportion being about seventy-five to one, so that by far the largest portion of the current passes through said main helix. The regulating-helix E is wound in a recess formed in the movable core, and is located in a shunt around the arc. It is so wound and connected that when, owing to the abnormal resistance of the arc, more of the current flows through it than through the main helix, it will induce magnetism in the movable core B of opposite polarity to that induced by the main helix A. The length of the arc is regulated as follows: The weight of the core being nearly balanced upon the springs Q, the tendency of the main helix A is to draw up the core B, and with it the upper carbon, thereby lengthening the arc and increasing the resistance at that point, the effect of which is to direct a portion of the current through the smaller helix, which, being of opposite polarity, operates by opposite induction to weaken the lifting-power of the main helix, so that the core will drop and the carbons will approach until the normal length of arc is re-established. If, from any cause, more than the intended quantity of current flows through the main helix A, the tendency would be to momentarily increase the length of the arc; but as that increases the resistance more current will flow through the opposing helix E, and as the increased magnetism of the helix A in the movable iron core B is met by a similar but opposite force from the helix E, any appreciable permanent change in the arc is prevented.

I am aware that a clutch has been heretofore provided which moves with the core of an axial magnet, the said clutch being adapted to be operated by magnetic repulsion instead of by magnetic attraction, as is shown in my lamp. It is found in practice impossible to operate by magnetic repulsion, because when the core is very magnetic, instead of repelling the clamp, it will attract it, just as a greater magnet will attract a lesser magnet, whichever pole of the lesser magnet be presented to the more powerful one. I do not claim in this application anything shown in the patent to W. H. and W. H. Markland, August 9, 1881, for electric-light regulator.

Without claiming the combination, in an elec-

tric lamp, of a helix in the main circuit, provided with a sliding core, a differential helix in a shunt around the arc, wound upon said core, and regulating mechanism for the carbons, connected to and actuated by said helices and core, what I claim as new, and desire to secure by Letters Patent, is—

1. The combination, in an electric lamp or regulator, of an axial magnet, its movable core, a secondary helix attached to and moving with said core, and a magnetic clamp attached to said core, but magnetically insulated from the same, the said clamp seizing the carbon-holder when attracted by the varying magnetism of the core, said magnetism being occasioned by the resultant of the magnetism induced by the external and the secondary coils, substantially as described.

2. An electric lamp provided with an outer main helix, a central movable core carrying a

regulating helix, a movable carbon-holder, and a clutch consisting of pivoted armature levers and rings controlled and regulated by the varying magnetism of the core, as shown and described.

3. The combination, in an electric regulator, of a principal coil with a hollow interior secondary or differential helix, which rises and falls by the varying magnetism of the main coil, and a carbon-holder centrally located with reference to the main and differential coils and passing through said differential coil, substantially as described.

In testimony whereof I have hereunto set my hand and seal in the presence of two subscribers.
